BY Amos W. Hart

ATTORNEY.

UNITED STATES PATENT OFFICE.

COLLIN C. GROOMES, OF BROOKLAND, DISTRICT OF COLUMBIA.

DESIGN FOR A BUTTON-BADGE.

SPECIFICATION forming part of Design No. 25,656, dated June 23, 1896.

Application filed May 18, 1896. Serial No. 592,064. Term of patent 31 years.

To all whom it may concern:

Be it known that I, COLLIN C. GROOMES, a citizen of the United States, residing at Brook-
5 land, in the District of Columbia, have in-
vented and produced a new and original De-
sign for Buttons or Badges, of which the fol-
lowing is a specification.

My invention is a new design for a "cam-
paign" button, badge, medal, or locket.

10 In accompanying drawing I illustrate a face
view of such design.

The leading feature of the design is the ar-
rangement, in a circle, on a disk *a*, of a series
15 of circular figures 1, a segmental portion or
crescent portion only surrounding a central
circular figure 2, the figures 1 in the circle

being inscribed or ornamented to represent
the faces of United States silver dollars, and
the central figure 2 representing the face of a
United States gold dollar.

20 A minor feature of the design is the ar-
rangement of three circular panels in the an-
nular space intervening the figures 1 and 2,
such panels affording space for any suitable
figures or other matter.

25

What I claim is—

The design for a button as shown and de-
scribed.

C. C. GROOMES.
